FIG. 14 is a right side elevation view of FIG. 9.

FIG. 15 is a top side plan view of FIG. 9.

FIG. 16 is a bottom side plan view of FIG. 9.

FIG. 17 is a top, right side isometric view of our new design for a body of a smart watch, all other surfaces being the same as the body of the embodiment of FIG. 1 other than the color.

FIG. 18 is a bottom, left side isometric view of FIG. 17.

FIG. 19 is a front side elevation view of FIG. 17.

FIG. 20 is a back side elevation view of FIG. 17.

FIG. 21 is a left side elevation view of FIG. 17.

FIG. 22 is a right side elevation view of FIG. 17.

FIG. 23 is a top side plan view of FIG. 17.

FIG. 24 is a bottom side plan view of FIG. 17.

FIG. 25 is a top, right side isometric view of our new design for a body of a smart watch, all other surfaces being the same as the body of the embodiment of FIG. 9 of application Ser. No. 29/706,975 other than the color.

FIG. 26 is a bottom, left side isometric view of FIG. 25.

FIG. 27 is a front side elevation view of FIG. 25.

FIG. 28 is a back side elevation view of FIG. 25.

FIG. 29 is a left side elevation view of FIG. 25.

FIG. 30 is a right side elevation view of FIG. 25.

FIG. 31 is a top side plan view of FIG. 25.

FIG. 32 is a bottom side plan view of FIG. 25.

FIG. 33 is a top, right side isometric view of our new design for a body of a smart watch, all other surfaces being the same as the body of the embodiment of FIG. 9 other than the color.

FIG. 34 is a bottom, left side isometric view of FIG. 33.

FIG. 35 is a front side elevation view of FIG. 33.

FIG. 36 is a back side elevation view of FIG. 33.

FIG. 37 is a left side elevation view of FIG. 33.

FIG. 38 is a right side elevation view of FIG. 33.

FIG. 39 is a top side plan view of FIG. 33.

FIG. 40 is a bottom side plan view of FIG. 33.

FIG. 41 is a top, right side isometric view of our new design for a body of a smart watch, all other surfaces being the same as the body of the embodiment of FIG. 9 other than color.
